UNITED STATES PATENT OFFICE.

WILLIAM J. CUMMINGS, OF JOLIET, ILLINOIS, ASSIGNOR TO SWEET, ORR & COMPANY, OF NEWBURGH, NEW YORK, A FIRM.

OVERALLS.

No. 905,796.

Specification of Letters Patent.

Patented Dec. 1, 1908.

Application filed April 30, 1908. Serial No. 430,202.

To all whom it may concern:

Be it known that I, WILLIAM J. CUMMINGS, a citizen of the United States, residing at Joliet, in the county of Will and State of Illinois, have invented a certain new and useful Improvement in Overalls, of which the following is a full, clear, and exact description.

Heretofore overalls have been provided with pockets for receiving tools, nails, and other articles, arranged in appropriate positions upon the garments so that they may be readily accessible by the wearers of the garments, but so far as I am aware, there has been no provision of a special pocket for carrying a handkerchief. So also overalls have heretofore been provided with safety watch pockets, but these pockets being on the outside accumulate dirt and gritty substances which mar or scratch the watch.

The object of this invention is to provide overalls with a pocket separate from the usual pockets for tools and other articles, which will be unexposed and yet in a convenient place to receive a handkerchief, and from which the handkerchief may be readily removed for use and as readily replaced.

A further object of the invention is to provide a safety watch pocket with openings at its bottom through which any dirt or gritty substance that may find its way into the pocket will escape, thus preventing the accumulation of such substances in the pocket and so avoiding injury to the watch.

The invention consists in overalls having a bib front provided with a lining or backing stitched thereto and left open at one edge to constitute a rear pocket, and a combined safety watch and pencil pocket having openings at its bottom for the escape of gritty substances from said pocket, all as I will proceed to now more particularly set forth and finally claim.

In the accompanying drawings, illustrating the invention, in the several figures of which like parts are similarly designated, Figure 1 is a front elevation. Fig. 2 is a rear elevation. Fig. 3 is a rear view, in perspective, showing the rear pocket slightly bulged with a handkerchief therein. Fig. 4 is a front elevation of the left hand portion of the bib front, showing the openings at the bottom of the watch pocket slightly bulged.

The invention is herein shown as applied to overalls of usual or conventional form or

pattern, but it is equally applicable to other forms or patterns of overalls wherein a bib front is employed, and to overalls and other garments of any kind wherein a watch pocket is desirable.

1 and 2 are the usual leg portions, provided with the usual front pockets 3, 3, and rear pocket 4, for the reception of tools and other articles.

5 and 6 are the usual shoulder-straps.

7 and 8 are the usual bib sections extending upwardly from the waist-line of the garment.

A lining or backing is secured to the bib section and stitched thereto in such manner as to form a space between said lining or backing and the material of the bib to constitute a pocket, the material of the bib and said lining or backing being left unstitched at a convenient place to form an entrance to said pocket.

As herein shown, and in the preferred construction, the right hand bib section 7 is provided at the rear with a lining or backing 9 which is secured to the bib section 7 by joining it thereto by the stitching at the center seam 10 of the two bib sections, and at the waist-line by a line of stitching 11. As shown in Figs. 2 and 3, the lining or backing 9 has its upper right hand corner cut at a greater angle or inclination than the inclination of the outer inclined edge of the bib section 7, and said edge is hemmed, as at 12, and left unstitched from the bib section, the remaining upper and outer edges of the lining or backing 9 being secured to the bib section by the lines of stitching 13 and 14, respectively, of the upper and side hems of the bib section.

The lining or backing 9 and the bib section 7 as thus constructed and stitched together form a convenient pocket for the reception of a handkerchief or any other article of use to a user of overalls, and when used for a handkerchief, the handkerchief may be placed therein and will be out of the way of the wearer and is readily accessible for use, and may as readily be replaced in the pocket. And furthermore, by the provision of this pocket, the other pockets of the overalls, which are provided for the reception of tools and other articles, will not be monopolized by the wearer's handkerchief.

The front of the left hand bib section 8 is provided with a combined safety watch and

pencil pocket, consisting of a piece of cloth 15 secured to the bib section at its inner edge by the stitching of the center seam 10 and at its bottom and outer edges by lines of 5 stitching 16 and 17, respectively, and provided with a short vertical opening or slit 18 opening into the safety watch pocket. The line of stitching 16 is interrupted a short distance from the opposite lower corners of the 10 pocket and preferably terminates in short vertical lines of stitching, thereby leaving portions of the hemmed lower edge of the piece 15 disconnected from the bib section to form vents or openings 19 at the lower 15 corners of the watch pocket, whereby any dirt or gritty substance that may find its way into the pocket will escape or be dislodged therefrom, and thus prevent the accumulation of such substances in the pocket to mar 20 or scratch the case of the watch. A line of stitching 20 to one side of the stitching 17 forms an upright pencil pocket. The upper edge of the piece 15 is secured to the bib section by a line of stitching 21 extending to 25 within a short distance of its outer edge to leave an entrance opening into the pencil pocket.

I have herein shown the handkerchief pocket formed upon the right hand side of 30 the bib only, but I wish to be understood as not limiting my invention to this arrangement of the pocket, as it is within my invention to arrange a pocket upon both sides of the rear of the bib, or a single pocket upon 35 either side thereof.

It is to be understood that the invention is not limited to any particular shape of watch pocket, or to any particular shape of the open bottom portion thereof, or to the number or location of the openings for the escape 40 of dirt, excepting in so far as such opening or openings are of a kind and arrangement

that will prevent the accumulation of dirt in the pocket.

What I claim is:—

1. Overalls, having a bib with a pocket on the rear or inside thereof, composed of the bib and a lining or backing stitched at its inner side edge and at its top and bottom edges to the bib, and also stitched to the 50 edge of the bib part way along its outer side edge, and left unattached along said edge from said outer side edge stitching to the upper part of the bib, thereby forming a mouth for the pocket arranged back of the edge of 55 the bib.

2. Overalls having a bib, a lining or backing secured at one edge to the center of said bib, and having its lower edge secured to said bib by a line of stitching at the waist line, 60 and having its upper corner cut at an angle to the side edge of the bib, and having the remainder of its top and side edges secured by the stitching of the hems at the upper and side edges of the bib respectively and the 65 cut-away edge left unstitched to form a side opening between said bib and lining or backing back of and inwardly from the edge of the bib, the material of the bib and said lining or backing constituting a pocket upon the rear 70 of the bib.

3. Overalls having a watch pocket constructed with unstitched portions at its lower corners with an intermediate stitched portion, to form openings at the opposite lower corners of the pocket for the escape of dirt and other gritty substances from the pocket.

In testimony whereof I have hereunto set my hand this 21st day of April A. D. 1908.

WILLIAM J. CUMMINGS.
